STOP LIGHT FOR AUTOMOBILES

Charles Joseph Montenotte, Detroit, Mich.

Application March 5, 1947, Serial No. 732,395

2 Claims. (Cl. 177—329)

1

My improvement falls into the class of signal lights for automotive vehicles, its specific purpose being to serve as a stop light to indicate that the driver of the vehicle equipped with said light is to be brought to a stop.

While a number of stop lights are already in use, the signal light of my invention includes certain features which make it more useful, said features being calculated to attract immediate attention of the driver or drivers within the range of vision of my stop light. This is due to a plurality of colored lights included in said signal and to the fact that these colored lights are flashed one by one, in rotation, so that a factor of movement is included in my stop light. As is well known, movement always makes an object more conspicuous and arresting.

In providing the stop light my object was also to develop a device of simple structure, compact in size and fully effective.

I wish now to describe my stop light with reference to the accompanying drawings in which:

Figure 1 is a perspective view of my stop light;

Figure 2 is a longitudinal sectional view of said light;

Figure 3 is a sectional view on line 3—3 of Figure 2;

Figure 4 is a sectional view on line 4—4 of Figure 2;

Figure 5 is a sectional view on line 5—5 of Figure 2;

Figure 6 is a sectional view on line 6—6 of Figure 3;

Similar numerals refer to similar parts throughout the several views.

The stop light includes a casing 10 substantially of a tear drop or barrel shaped design, and is affixed to the body of the automobile by suitable means including such means as brackets which are not shown. In the form disclosed in the drawings, one end of the casing is of a larger diameter than the opposite one, and it is at this end of the larger diameter, that it is fitted with a flat cover 11. The cover is provided with a circular aperture occupied by a diffusing lens 12, preferably made of transparent red glass or other suitable material. Disposed around said lens in a circular arrangement, is a number of apertures, each serving as a frame for a colored lens or a colored pane 13. Mounted within the casing, at the narrowed end thereof, and axially disposed therein, is a small electric motor 14 supported in its place by means of brackets 15. The motor is of a low voltage variety, designed to operate on the current supplied by a standard automobile

2

battery of six volts. The shaft 16 of the motor fits axially into a cylindrical coupling 17 made of a suitable dielectric material such as Bakelite, fiber, hard rubber, etc. A disk 18 carried by the coupling and axially aligned therewith, rotates with said coupling and carries two electric light bulbs. One of them 19, is held within a socket 20. The socket provided with a bayonet slot is located radially along the rim of the disk so that the bulb itself, held therein, is located centrally with respect to said disk, and directly back of the diffusion lens 12. The other bulb 22, is held within a socket 23, turned outwardly of the disk so that said bulb projects beyond the rim of the disk, and with the rotation thereof will be carried along a circular path back of the colored panes 13.

Electric current necessary to operate the stop light is supplied by an ordinary storage battery 20 of the type commonly used in automobiles. It is this low voltage current which will operate said motor 14. A cable leading from the battery to the motor is shown by numeral 24. The current to the bulbs is supplied by a separate cable 25 including two wires, one 26 carrying the current from the battery to the bulbs, the other 27, being the lead line from the bulbs to the battery. Separated, the wires are connected to resilient contact points or fingers 28 and 29, respectively. The fingers are mounted on a small plate 30 which is kept in place by a metal bracket 31 secured by a screw 32 to the casing of motor 14, and bear against annular conductors 33 and 34 respectively. The conductors are made of metal and are seated axially on a coupling which is made of a dielectric material. One of said conductors is soldered directly to the disk 18. Electric current passing through wire 36 and through the contact finger 28, is gathered by said annular conductor 34. As said conductor 34 and the disk are soldered together and as said conductor is made of metal and sockets 20 and 23 are mounted thereon, electric current will be thus carried to said sockets. A spring clip 35 mounted on disk 18, insulated therefrom by a plate 39, reaches into the bottom of the socket 20, but without touching it, and a similar spring clip 36, similarly mounted on the disk and insulated by a plate 40, reaches into the bulb of socket 23 as best shown in Figures 2 and 4. The spring clips are in contact with the respective, centrally located terminals, in the bases of bulbs 19 and 20. A wire 41 connects the two clips and joins wire 37, which leads into the body of the coupling 17. The respective length 38 of the wire within said

coupling, is soldered to the annular conductor 33. Therefrom, a suitable conductor to the battery will close the circuit.

As the stop light is to operate only when the car is about to be brought to a stop, one of the leads from the stop light to the battery is provided with a switch. The switch may be operated by the foot brake of the automobile. However, as this is only an incidental matter, and as the novelty disclosed herein lies not in the combination of the brake with the stop light but in the design of the stop light itself, these details pertaining to the switch and to the foot brake are omitted. The matter of such a connection would be obvious to any one familiar with the construction of an automobile.

Having described the above stop light, what I wish to claim is as follows:

1. A stop light of the kind described comprising a barrel-like casing provided with a flat end cover having a central opening framing a red lens and a plurality of openings arranged in a circle around said red lens, each of said openings framing a transparent pane of different color, a motor at the opposite end of the casing, the motor having a shaft, axially disposed within the casing, a dielectric coupling cylinder mounted on said shaft and carrying a disk spaced from the lens carrying end, a light bulb located centrally on the disk and another light bulb on the marginal portion thereof at a radial distance from the center equal to that of the respective lenses from the central one, the bulbs being located on the side of the disk facing the cover, two metal rings axially mounted on the coupling and spaced from each other, wire conductors leading from one ring to the bulbs and from the bulbs to the

other ring, resilient metal fingers in contact with said rings and current conducting means to the motor and to said fingers.

2. A stop light of the kind described comprising a substantially cylindrical casing having at one end a cover provided with a central opening, framing a red lens and with a plurality of openings framing lenses of different colors and arranged in a circular arrangement around said central red lens, an axially disposed shaft within the casing, a cylindrical coupling of dielectric material axially connected with the shaft and carrying a disk disposed back of the cover and spaced therefrom, a centrally located light bulb on the disk on the side of the cover and a marginally disposed light bulb for display behind the lenses of the circular arrangement, two metal rings on the coupling, current conducting means from one ring to the bulbs and current conducting means from the bulbs to the other ring, resilient metal fingers in contact with the rings, motor means to rotate such shaft and wire means to supply current for the operation of the motor and to the fingers for lighting the said bulbs.
